UNITED STATES PATENT OFFICE.

AMOS W. WENTZELL, OF SALEM, NEW JERSEY.

SCREEN DEVICE FOR CASEMENT WINDOWS.

Application filed October 30, 1926. Serial No. 145,238.

The present invention relates to screening for casement windows and aims to provide a structure which may be easily operated and is efficient and reliable in use.

Another important object of the invention lies in the provision of a casement window screen of this nature which is simple in its construction, inexpensive to manufacture, strong and durable, one which affords ready and easy access to the casement windows for operation thereof and is otherwise well adapted to the purpose for which it is designed.

With the above and numerous other objects in view, as will appear as the description proceeds, the invention resides in the novel features of construction, and in the combination and arrangement of parts as will be hereinafter more fully described and

claimed.

In the drawings:

Figure 1 is an inside end elevation of a casement window frame with my improved screen construction mounted therein,

Fig. 2 is an enlarged detail horizontal section taken substantially on the line 2-2 of Figure 1 looking downwardly,

Fig. 3 is another enlarged detail horizontal section taken substantially on the line 3-3 of Figure 1 looking downwardly,

Fig. 4 is a detail perspective view of one of the locking bolts.

Referring to the drawing in detail it will be seen that the numeral 5 denotes the top of the window frame having sides 6 and a button sill 7. The usual casement windows 8 are mounted in the frame to swing outwardly thereof in the usual well-known manner. The usual or any preferred means 9 is illustrated for holding the windows 8 opened or closed in the well-known manner.

The main frame of the screen structure is denoted by the letter F and is rectangular in formation and is held within the casement window frames by means of screws 10 or like fastening elements. This frame F is formed of sheet steel to provide a top rail 11 and a bottom rail 12 and side rails 14. These rails are of L-shaped cross section and are hollow as may be seen in Figures 2 and 3. The side rails 14 have their inside edges formed with tenons 15 extending longitudinally thereof. The outside faces of the side rails and the upper halves thereof are provided with recesses 16 for receiving

portions of a foraminous sheet 17 which is held in place by bars 18 shaped to fill the recesses 16 and held in place by screws 19. A center rail 20 extends vertically between the centers of the top and bottom rails 11 and 12 and is formed at its opposite edges with tenons 15. Two sashes S are slidably mounted between the side rails 14 and the center rail 20. Each sash includes a rectangular frame formed of sheet steel and the sides 21 thereof have their outer edges formed with longitudinally extending mortises 22 for receiving tenons 15. These tenons 15 hold the sashes S in place and allow them to slide to a raised position such as is shown in the right hand portion of Figure 1 so that access may be had to the casement windows 8 for opening or closing the same. The frames of the sashes S have mounted therein sheets of foraminous material indicated at 24. The rails of the frame of each sash S are provided with recesses 25 for receiving the edges of the sheet 24 and blocks 26 which are held in place by screws 27. The lower rails of the frames of the sashes S are provided with hand holds 28 so that these sashes S may be easily lowered and raised. In order to lock the sashes in their lowered positions in order that they may not be raised from the outside I have provided a pair of bolts B one in each side rail 14 adjacent the lower ends thereof as is clearly illustrated particularly in Figures 2 and 3. Each bolt B includes the bolt proper 29 which is slidable through an opening in the lower portion of the tenon 15 of the respective rails 14. At one end of the bolt proper 29 there is provided a lateral extension 30 which terminates within the flange-like portion 31 of the respective rail 14 and has a shank 32 extending parallel with the bolt proper 29 and through an opening 33 in the portion 31. Springs 34 are mounted between the extensions 30 and one side of the respective rail 14 so as to normally hold the bolts proper 29 in an extended position for engaging in an opening 35 provided in the respective mortise 22 thus preventing the raising of the sash. Obviously, the shank 32 may be pushed inwardly to release the bolt and allow the sash to be raised.

It is thought that the construction, utility, and advantages of my invention will now be clearly understood and appreciated by those skilled in this art without a more extended explanation. It is desired, how-

ever, to point out that the structure is sturdy, strong and durable and is capable of allowing the necessary replacement at a minimum cost particularly in the renewal 5 of the screened sheets as may become necessary from time to time through wear, rot, and breakage. The present embodiment of the invention has been disclosed in detail merely by way of example since in actual 10 practice it attains the features of advantage enumerated as desirable in the statement of the invention and the above description. It will be apparent that changes in the details 15 of construction and in the combination and arrangement of parts may be resorted to without departing from the spirit or scope of the invention as hereinafter claimed or sacrificing any of its advantages.

Having thus described my invention, what 20 I claim as new is:—

1. A screen structure of the class described including a frame having hollow side rails provided with hollow tenons extending inwardly therefrom and longitudinally thereof and lateral hollow flanges on

the sides thereof, a bolt slideable through an opening in one of the tenons and having a laterally extending arm in the hollow flange, a pin projecting from the arm, a spring on the pin impinging against the interior of 30 the hollow flange and the side rail for the purpose of holding the bolt normally extended through the opening in the tenon, said flange having an opening, a knob on the arm projecting through the opening, and a sash having mortises to receive the tenons, said sash having an opening in the bottom of one of its mortises to receive the bolt. 35

2. In a window screen frame structure of the class described, a frame member comprising a hollow side rail provided with a hollow tenon extending inwardly and longitudinally of said frame, a lateral hollow flange on one side of the rail, said rail having a recess exteriorly of the frame, and a bar in the recess for holding a portion of mesh sheet in the recess besides reinforcing the hollow rail. 40

In testimony whereof I affix my signature.

AMOS W. WENTZELL.
